UNITED STATES PATENT OFFICE

JOHN SELDEN, OF ST. JOHNS, QUEBEC, CANADA, ASSIGNOR OF FORTY-NINE ONE-HUNDREDTHS TO HERMAN ZOTTI

LOOSE-LEAF SHEET

Application filed April 3, 1928, Serial No. 267,004. Renewed February 13, 1930.

This invention relates to new and useful improvements in loose leaf sheets for loose-leaf note books, ledgers, and the like. The main object of the invention is to provide an 5 inexpensive sheet so reinforced that it will not tear or become loose from the attaching medium due to rough usage.

Up to the present time, it has been found a difficult matter to obtain an inexpensive 10 looseleaf sheet which would stand the rough usage that they are subjected to. Sheets have been manufactured with linen reinforcing strips along one edge, but these strips are expensive to manufacture and are easily torn. 15 According to my invention I provide a sheet of paper having a metallic reinforcing medium secured to one edge thereof, and said medium is perforated for attaching same to the clips of a looseleaf ledger.

20 In the drawings which illustrate my invention:—

Figure 1 is a perspective view of my preferred form of loose leaf sheet.

Figure 2 is a sectional plan taken on the 25 line 2—2 Figure 1.

Figure 3 is a part perspective view of a modified type of the sheet shown in Figure 1.

Figure 4 is a view similar to that shown in Figure 3, but showing a further modification 30 which may be made to the sheet shown in Figure 1.

Referring more particularly to the drawings, 10 designates a sheet of paper and secured to one marginal edge thereof by an adhesive 35 is a very thin metallic strip 11, provided with a plurality of perforations 12. In Figure 1 these perforations are spaced from the edges of the strip and are preferably punched through the paper and the strip as 40 shown.

In Figure 3 the metallic strip 11^a is secured along one marginal edge of the sheet 10^a and the perforations 12^a are punched in the paper only. The edges of the perforations are preferably placed as close as possible to the edge 11^b of the metallic strip. In Figure 4 the 45 perforations 12^b are punched in the metallic strip 11^c only and the edge 11^d of said strip overlies and is secured to the marginal edge 50 of the paper 10^b by any suitable means.

The metallic strip reinforces the sheet and prevents tearing of same through the perforations when the leaf is attached to the staples or hooks of a looseleaf note book, ledger, or the like. The metallic strips can be 55 very easily manufactured and when attached to the paper sheet form a reinforcement for same which will practically eliminate tearing of the sheets through the perforations. The metallic strip toughens the edge of the sheet and does not detract from it any of its flexibility.

Having thus described my invention, what I claim is:—

1. A loose leaf, comprising a sheet of paper having secured thereto and along one marginal edge, a thin strip of metal, said strip and sheet being perforated for attaching to the staples of a looseleaf ledger or the like. 65

2. A looseleaf, comprising a sheet of paper having secured thereto by means of an adhesive, a thin metallic reinforcing strip, said strip being along one marginal edge of the paper, the strip having perforations formed therein for securing the sheet to staples and 70 the like.

3. A loose leaf comprising a sheet of paper, a thin highly flexible strip of aluminum adhesively united to one face of said sheet and positioned to extend along one edge of the 75 sheet to provide a flexible reinforcement therefor.

In witness whereof, I have hereunto set my hand.

JOHN SELDEN. 85
